ENGINE LUBRICATOR

Emmet M. Green, Los Angeles, Calif.

Application June 6, 1941, Serial No. 396,817

22 Claims. (CL 123—196)

This invention relates to improvements in lubricators, particularly of the type adapted to be used for engine head and valve lubrication, and has for its general object to accomplish both lubrication and solvent treatment of the engine parts efficiently and in direct accordance with the requirements of the parts for such treatment.

The past has produced various kinds of engine head lubricators, some operating to deliver a continuous feed of lubricant into the air stream taken by the engine, while other supply the lubricant intermittently and at the time of starting the engine in operation. The present device is of an intermittent delivery type, but operates differently in certain fundamental and distinctly advantageous respects, from all prior lubricators of which I am aware. The characteristic mode of operation of those lubricators that deliver to the engine a single, as distinguished from a continuous charge of lubricant, is to cause such delivery to occur during and for a short period following starting of the engine in operation, with recharging of the lubricant metering parts of the device occurring while the engine is stopped. Illustrative of this general type is my copending application Serial No. 256,146, filed February 13, 1939, on Lubricator, now Patent Number 2,267,728.

As shown in my copending application Serial No. 394,690, filed May 22, 1941, there has also been developed a lubricator which will provide either a single charge of lubricant at the start of the engine operation or a continuous supply of lubricant.

Some of the heretofore proposed intermittent delivery type lubricators are inherently objectionable and wasteful of lubricant in that they operate to deliver a charge to the engine each time it is started, and at times when the engine parts do not require lubrication. This objection is overcome by the invention of my copending application mentioned above, in that it permits delivery of the lubricant charge only after the engine has been stopped for an extended period of time during which, under all normal conditions, the engine will have cooled. However, it is found that even such delayed responsiveness will not meet certain requirements for more perfect lubrication under all conditions of engine operation, and particularly for the most effective solvent treatment of the parts to be contacted by the lubricant. For example, delivery of lubricant only at the start of engine operation may not adequately lubricate and solvent treat the engine valves and upper cylinder walls while the engine is in continuous operation over an abnormally long period of time.

The present invention departs from past practices in that instead of controlling the supply of successive lubricant charges to the engine in ac-

cordance with its starting and stopping, or with relation to a predetermined length of time after the engine is stopped, the interval between deliveries of successive charges is governed generally by the extent to which the engine actually has been in operation, and specifically in accordance with a predetermined period of operation, whether that period be continuous or the aggregate of intermittent shorter periods of operation. Since it may be said that as a general proposition, the need for lubrication and solvent treatment is a direct function of the extent (total revolutions or length of time) the engine has been in operation, the advantages and desirability of thus controlling delivery of the lubricant are readily appreciated. Thus, assuming for example a condition of continuous engine operation over a time period of such duration that the engine requires lubrication more than once, it is important that the lubricator be capable, as I have provided, of metering and delivering the individual charges after extended intervals, while the engine remains in operation. Conversely, it is also important where successive engine operating periods are short, that the lubricant delivery be withheld until the end of an aggregate operating period when lubrication is needed.

In addition to its functional advantages the present lubricator is characterized by its capacity for extremely simple and economical manufacture. Although, as will be understood, the invention is capable of various particular forms and embodiments, typically and preferably it is made to comprise a simple arrangement of a lubricant reservoir, a supply chamber, and equally simple communications between the reservoir and supply chamber, and between the latter and the engine, whereby operation of the engine produces delivery of lubricant from the reservoir at a predetermined (slow) rate into the supply chamber, and intermittent deliveries of predetermined or measured charges of the lubricant from the chamber to the engine after predetermined intervals based on actual operation of the engine.

A better understanding of the above mentioned features of the invention, as well as of additional objects and the details of a typical and preferred embodiment as referred to above, will be had from the following description and the accompanying drawing, in which:

Fig. 1 is a vertical sectional view of the apparatus; and

Fig. 2 is a fragmentary section illustrating a variational feature of the invention.

The body of lubricant 10 from which successive charges are taken for intermittent delivery to the engine, may be contained in a suitable reservoir such as a container 11 closed at its top by a suitable cap 12 which may have a screw threaded

connection at 13 with the container proper. The device may be supported at the rear of an automobile engine, as on the usual body panel, in any suitable manner, as for example by a bracket 14 formed integrally with the cap 12. Lubricant is delivered to the engine through a conduit 15 which may connect into the engine manifold, not shown, or at any other suitable location, and through which the engine-created suction is communicated to the interior of the reservoir. It will be understood that the particular form of the container 11 and its closure 12 may be modified as desired to adapt the parts to the use of individual containers or cans in which the lubricant may be sold.

The lubricant supply chamber 16, which need consist merely of a cup-shaped container 17 and a top closure 18 screw threaded or otherwise attached at 19 to the container 17, is mounted within the upper interior of the reservoir as by means of supports 20 suspending the chamber assembly from cap 12 of the reservoir. During operation of the engine, lubricant is supplied from body 10 to the chamber 16 through orifice 21 in the bottom of the depressed portion 22 of the chamber cover 18, the rate of lubricant delivery into the chamber being determined by the effective size of orifice 21. In the form of the invention shown in Fig. 1, this effective orifice size may be varied to increase or decrease the rate of lubricant delivery into the supply chamber, by an adjustable needle valve 23 having a threaded stem extending at 24 through the cap 12, as illustrated.

The top surface of the supply chamber may or may not have the cavity 22 above the metering orifice 21. If used, the cavity may be regarded as forming a secondary chamber within which a predetermined or constant head of lubricant is maintained above the orifice, and from which an amount of lubricant, depending upon the volume of the cavity, will drain through the orifice to supplement the oil in the supply chamber, after the engine is stopped.

Lubricant may be elevated from the body 10 for delivery through orifice 21 to the supply chamber, by a suitable air lift or pump 25 and comprising, for example, an air inlet tube 26 extending downwardly from its communication through filtering material 27 with the atmosphere, toward the bottom of the reservoir and having a nozzle end 28 discharging into a riser tube 29. Lubricant enters tube 29 through openings 30 below the outlet or nozzle 28 of tube 26. During engine operation, the depression within the reservoir causes air to be drawn in through tube 26 and the oil entering tube 29 through openings 30, to be carried upwardly with the air stream through tube 29 and discharged at 31 directly above the cavitation 22 in the supply chamber cover. A screen 32 is placed above the orifice 21 to prevent clogging of the orifice by any solid or gummy particles present in the oil. The rate of lubricant discharge through tube 29 will be in excess of the rate of lubricant feed through orifice 21 into the supply chamber, and the excess oil simply overflows the top of the chamber and returns to the lubricant body 10. Pressure equalization between the reservoir and the supply chamber may be assured by maintaining a suitable open communication between the two, as by means of a bent tube 33 extending through the cover of the chamber.

Provision is made for automatically causing delivery to the suction line 15 of a lubricant charge accumulated to predetermined volume in

the supply chamber 16, by a siphon tube 34 extending through the bottom of the chamber and discharging into the enlarged mouth 35 of conduit 15 placed directly below the outlet end of the siphon tube. The latter may be centrally positioned within the supply chamber, bringing the highest overflow point 34a of the tube in alignment with the vertical axis of the chamber, in order to minimize variations in the quantity of charge siphoned through the tube, as might result from inclining or tipping of the chamber.

Reference has been made to the showing in Fig. 1 of an adjustable needle valve 23 for controllably varying the rate of oil flow into the supply chamber, and the period during engine operation, required for accumulation of the charge to be delivered to the engine. The period between deliveries of successive charges may also be varied, as shown in Fig. 2, by maintaining, under given pressure conditions, uniform rate of oil delivery to the supply chamber and varying in effect the volume of the chamber to be occupied by the charge before its removal by the siphon. In Fig. 2 the oil is shown to enter the supply chamber through a constant-size orifice 37 about an adjustable stem 38 threaded through the cap at 39 and connected at 40 with a flexible free end portion 41a of the siphon tube, the lower part 41 of which is rigid and affixed to the bottom wall of the chamber 17. The connection at 40 may consist typically of a projection 42 carried by the flexible tube 41a and having its under-side engaged by the head 43 of stem 38. When turned, the latter rotates within the projection 42 and elevates or lowers the bend of the tube 41, thereby varying the depth to which the lubricant must accumulate in the chamber before overflowing through the siphon.

The form of the invention shown in Fig. 2 may have an advantage for certain operating requirements, independently of the function of the siphon tube adjustment for varying the length of time required for accumulation of the charge. I refer here to the capacity of the adjustment for controllably varying the volume of the charge and the adaptability of the device to supply greater volume charges at longer intervals, or smaller volume charges at reduced intervals. As a specific illustration, where the engine is operated over an average short period of time, or with frequent startings and stoppings, it may be desirable to supply the engine with smaller volume lubricant charges, and at shorter intervals. This of course may be done simply by lowering the overflow height of the siphon to reduce the volume of the charge and correspondingly decrease the period between deliveries of successive charges.

As previously observed, the invention is particularly advantageous by reason of its mode of operation, for the delivery of lubricants which contain solvents or have solvent properties with respect to carbonaceous deposits on the engine parts to be contacted by the lubricant. Accordingly, the operating and timing characteristics of the lubricator are controlled and predetermined in contemplation of both proper lubrication and solvent treatment of the engine parts.

In operation, upon starting of the engine the depression communicated through tube 15 to the lubricator starts delivery of the oil through tube 29 and orifice 21 into the supply chamber 16, all as previously explained. In general, the point at which the lubricant charge will be delivered through the siphon tube 34 will depend upon

the rate at which the charge accumulates to a predetermined quantity or volume in the supply chamber. Under normal conditions of engine operation, lubrication and solvent treatment of the engine parts are not required at intervals shorter than periods of about one hour, or even two or three hours, based on the time of continuous or actual engine operation. Valve 23 in Fig. 1, or the tube 41 in Fig. 2, therefore is adjusted accordingly. When the lubricant accumulates in the supply chamber to the level L—L₁ of overflow through the siphon tube, the charge is delivered to the suction conduit 15 (at a rate which may be controlled by the effective size or diameter of the siphon tube) to be taken into the engine. Thereafter, a successive charge accumulates within the supply chamber, but only while the engine is operating, to be delivered at the end of a determined period or extended engine operation. As will be apparent, whatever amount of lubricant is present in the supply chamber when the engine is stopped, will remain to be supplemented by additional lubricant when the engine again starts into operation.

I claim:

1. In an engine lubricator of the character described, a lubricant reservoir, a supply chamber, means operable by suction created by running of the engine for delivering a predetermined charge of lubricant from said reservoir to the chamber during running of the engine, and means operable as the engine continues to run and when said charge has been delivered to the chamber to feed the charge to the engine and to then discontinue the lubricant feed thereto.

2. In an engine lubricator of the character described, a lubricant reservoir, a supply chamber, means operable by and only during communication of suction created by running of the engine for delivering at least the greater portion of a predetermined charge of lubricant from said reservoir to the chamber, and means operable as the engine continues to run and when said charge has been delivered to the chamber to feed the charge to the engine and to then discontinue the lubricant feed thereto.

3. In an engine lubricator of the character described, a lubricant reservoir, a supply chamber, means operable by and during continuous running of the engine for successively delivering predetermined charges of lubricant from said reservoir to the chamber, and means operating intermittently and when each charge has been delivered to the chamber, to feed said charges to the engine, the intermittent operation of the last mentioned means being controlled in accordance with the accumulation of individual lubricant charges in said chamber.

4. In an engine lubricator of the character described, a lubricant reservoir, a supply chamber, means operable by and during continuous running of the engine for successively delivering predetermined charges of lubricant from said reservoir to the chamber at intervals of at least one hour, and means operating intermittently and when each charge has been delivered to the chamber, to feed said charges to the engine.

5. In an engine lubricator of the character described, a lubricant reservoir, a supply chamber, means operable by suction created by and during continuous running of the engine for successively delivering predetermined charges of lubricant from said reservoir to the chamber, and means operating intermittently and when each charge has been delivered to the chamber, to feed said

charges to the engine, the intermittent operation of the last mentioned means being controlled in accordance with the accumulation of individual lubricant charges in said chamber.

6. In an engine lubricator of the character described, a lubricant reservoir, a supply chamber, means operable by and during continuous running of the engine for successively delivering predetermined charges of lubricant from said reservoir to the chamber, and means operating intermittently and when each charge has been delivered to the chamber, to at least partially empty the chamber of lubricant and feed said charges to the engine, and to discontinue the feed of lubricant to the engine between its said intermittent operations.

7. In an engine lubricator of the character described, a lubricant reservoir, a supply chamber, means operable by the engine suction for elevating lubricant from the body of lubricant in said reservoir and delivering a predetermined charge of the elevated lubricant into the supply chamber during running of the engine, and means operable when the charge has been delivered to the chamber to at least partially empty the chamber of lubricant and feed the charge to the engine.

8. In an engine lubricator of the character described, a lubricant reservoir, a supply chamber, means operable by the engine suction for elevating lubricant from the body of lubricant in said reservoir and delivering a predetermined charge of the elevated lubricant into the supply chamber at a relatively slow rate through a restricted orifice during running of the engine, and means operable when the charge has been delivered to the chamber to feed the charge at a relatively fast rate from said chamber to the engine.

9. In an engine lubricator of the character described, a lubricant reservoir, a supply chamber, means operable by the engine suction for elevating lubricant from the body of lubricant in said reservoir and delivering a predetermined charge of the elevated lubricant into the supply chamber, and a siphon operable when the charge has been delivered to the chamber to withdraw the charge therefrom for delivery to the engine.

10. In an engine lubricator of the character described, a lubricant reservoir, a supply chamber, means operable by the engine suction for elevating lubricant from the body of lubricant in said reservoir and delivering a predetermined charge of the elevated lubricant into the supply chamber, a siphon operable when the charge has been delivered to the chamber to withdraw the charge therefrom for delivery to the engine, and means for communicating the engine suction pressure uniformly to both said chamber and the reservoir.

11. In an engine lubricator of the character described, a lubricant reservoir, a supply chamber contained within the upper interior of the reservoir, means operable by engine-created suction communicated to the reservoir for elevating lubricant from the body of lubricant in the reservoir and delivering the elevated lubricant into a predetermined volume of the supply chamber through a restricted orifice which times the rate of lubricant delivery to the chamber, a siphon operable only when said volume of the supply chamber is filled to withdraw a corresponding charge of lubricant therefrom, and a conduit through which said charge is drawn into the engine.

12. In an engine lubricator of the character described, a lubricant reservoir, a supply chamber

contained within the upper interior of the reservoir, means operable by engine-created suction communicated to the reservoir for elevating lubricant from the body of lubricant in the reservoir and delivering the elevated lubricant into a predetermined volume of the supply chamber through a restricted orifice which times the rate of lubricant delivery to the chamber, means for equalizing the reservoir and supply chamber pressures, a siphon operable only when said volume of the supply chamber is filled to withdraw a corresponding charge of lubricant therefrom, and a conduit through which said charge is drawn into the engine.

13. In an engine lubricator of the character described, a lubricant reservoir, a supply chamber contained within the upper interior of the reservoir, means operable by engine-created suction communicated to the reservoir for elevating lubricant from the body of lubricant in the reservoir and delivering the elevated lubricant into a predetermined volume of the supply chamber through a restricted orifice which times the rate of lubricant delivery to the chamber so that said volume of the chamber is filled in a period not less than about one hour, a siphon operable only when said volume of the supply chamber is filled to withdraw a corresponding charge of lubricant therefrom, and a conduit through which said charge is drawn into the engine.

14. In an engine lubricator of the character described, a lubricant reservoir, a supply chamber contained within the upper interior of the reservoir, means operable by engine-created suction communicated to the reservoir for elevating lubricant from the body of lubricant in the reservoir and delivering the elevated lubricant into a predetermined volume of the supply chamber through a restricted orifice which times the rate of lubricant delivery to the chamber, means for controllably varying the rate of lubricant delivery through said orifice, a siphon operable only when said volume of the supply chamber is filled to withdraw a corresponding charge of lubricant therefrom, and a conduit through which said charge is drawn into the engine.

15. In an engine lubricator of the character described, a lubricant reservoir, a supply chamber contained within the upper interior of the reservoir, means operable by engine-created suction communicated to the reservoir for elevating lubricant from the body of lubricant in the reservoir and delivering the elevated lubricant into a predetermined volume of the supply chamber through a restricted orifice which times the rate of lubricant delivery to the chamber, means for controllably varying said volume of the chamber, a siphon operable only when said volume of the supply chamber is filled to withdraw a corresponding charge of lubricant therefrom, and a conduit through which said charge is drawn into the engine.

16. In an engine lubricator of the character described, a lubricant reservoir, a supply chamber, means operated by the engine for continuously transferring lubricant from said reservoir to said supply chamber, means controlled by the delivery of lubricant to said chamber for intermittently delivering predetermined charges of lubricant from said supply chamber, and means operated by the engine suction for delivering said removed charges to the engine.

17. In an engine lubricator of the character described, a lubricant reservoir, a supply cham-

ber, means operated by said engine for continuously transferring lubricant from said reservoir to said supply chamber, means controlled by the delivery of lubricant to said chamber for intermittently removing predetermined charges of lubricant from said supply chamber, and means operated by the engine suction for delivering said removed charges to the engine during continuous operation of the engine.

18. In an engine lubricator of the character described, a lubricant reservoir, a supply chamber, means operated by said engine for continuously transferring lubricant from said reservoir to said supply chamber, means controlled by the delivery of lubricant to said chamber for intermittently removing charges of lubricant from said supply chamber, means operated by the engine suction for delivering said removed charges to the engine during continuous operation of said engine, and means for varying the size of said charges.

19. In an engine lubricator of the character described, a lubricant reservoir, a supply chamber, means operated by said engine for continuously transferring lubricant from said reservoir to said supply chamber, means controlled by the delivery of lubricant to said chamber for intermittently removing charges of lubricant from said supply chamber, means operated by the engine suction for delivering said removed charges to the engine during continuous operation of said engine, and means for varying the time interval between removal of said intermittent charges from the chamber.

20. In an engine lubricator of the character described, a lubricant reservoir, a supply chamber, means operable by and during running of the engine for delivering a predetermined charge of lubricant from said reservoir to the chamber, means controlled by the accumulation of lubricant in the chamber for removing the charge therefrom, and means operable by engine-created suction to feed the removed charge to the engine and to automatically discontinue such feed upon the removal of said charge from the chamber.

21. In an engine lubricator of the character described, a lubricant reservoir, a supply chamber, means operable by and only during running of the engine for delivering at least the greater portion of a predetermined charge of lubricant from said reservoir to the chamber, means controlled by the accumulation of said charge above a predetermined level in the chamber and operable to remove the charge from above that level, and means operable by engine-created suction to feed the removed charge to the engine and to automatically discontinue such feed upon the removal of said charge from the chamber.

22. In an engine lubricator of the character described, a lubricant reservoir having lubricant in the lower portion thereof, a supply chamber, a discharge passage having one end open to the reservoir above the lubricant level and the other end connected to the engine suction line, means operable by and during running of the engine for delivering lubricant from said reservoir to the chamber, and means for feeding lubricant from said chamber to the open end of said discharge passage, the last mentioned means operating to discontinue such feed of lubricant upon removal of a predetermined amount of lubricant from said chamber.

EMMET M. GREEN.
